(57) **CLAIM**

The ornamental design for an earpiece and case set as shown and described.

DESCRIPTION

FIG. 1 is a perspective view of an earpiece and case set showing the new design with the case empty;

FIG. 2 is another perspective view of the earpiece and case set showing the case empty thereof;

FIG. 3 is a front elevational view of the earpiece and case set showing the case empty thereof;

FIG. 4 is a rear elevational view of the earpiece and case set showing the case empty thereof;

FIG. 5 is a left side view of the earpiece and case set showing the case empty thereof;

FIG. 6 is a right side view of the earpiece and case set showing the case empty thereof;

FIG. 7 is a top plan view of the earpiece and case set showing the case empty thereof;

FIG. 8 is a bottom plan view of the earpiece and case set showing the case empty thereof;

FIG. 9 is a perspective view of the earpiece and case set, the earpiece is shown separately for ease of illustration thereof;

FIG. 10 is another perspective view thereof;

FIG. 11 is a front elevational view thereof;

FIG. 12 is a rear elevational view thereof;

FIG. 13 is a left side view thereof;

FIG. 14 is a right side view thereof;

FIG. 15 is a top plan view thereof;

FIG. 16 is a bottom plan view thereof; and,

FIG. 17 is a perspective view of the earpiece and case set in an open position.

The broken lines depict portions of the earpiece and case set that form no part of the claimed design.

1 Claim, 17 Drawing Sheets
